DESIGN FOR AN AUTOMOBILE

George J. Keller, East St. Louis, Ill.

Application May 14, 1935, Serial No. 56,825

Term of patent 7 years

To all whom it may concern:

Be it known that I, George J. Keller, a citizen of the United States, residing at E. St. Louis, in the county of Saint Clair and State of Illinois, have invented a new, original, and ornamental Design for an Automobile, of which the following is a specification, reference being had to the accompanying drawings, forming part thereof.

Figure 1 is a view in side elevation of an automobile, showing my new design.

Figure 2 is a top plan view thereof.

Figure 3 is a front elevational view.

Figure 4 is a rear elevational view.

I claim:—

The ornamental design for an automobile, as shown.

GEORGE J. KELLER.
